United States Patent Office

Des. 213,577
Patented Mar. 18, 1969

213,577

BEVERAGE SERVER

David Douglas, 1119 Lincoln Blvd.,
Manitowoc, Wis. 54220

Filed Dec. 21, 1967, Ser. No. 9,873

Term of patent 14 years

U.S. Cl. D44—21
Int. Cl. D7—01

FIG. 1 is a perspective view of a beverage server showing my new design;

FIG. 2 is a side elevational view;

FIG. 3 is a front elevational view;

FIG. 4 is a top plan view; and

FIG. 5 is a bottom plan view.

I claim:

The ornamental design for a beverage server, substantially as shown.
